UNITED STATES PATENT OFFICE

HENRY C. BRENNAN, OF WICKFORD, RHODE ISLAND

FLUSH TANK CONTROL VALVE

Application filed June 12, 1929. Serial No. 370,347.

This invention relates to an improved discharge or control valve construction for use in association with flush tanks such as are employed with present day toilet and bath-
5 room closets.

The purpose of the invention is to provide a valve which permits complete drainage of the water from the flush tank and to so construct the valve as to facilitate its installation in a practical and satisfactory manner in conventional flush tanks.

In carrying the invention into effect, I have evolved and produced what I believe to be an unusually practical arrangement of 15 details expressly made for intimate cooperation with each other in a manner to provide an efficient valve arrangement which will fulfill the requirements of a structure of this class in a more satisfactory manner than 20 those now known to me.

The specific details and their association will become more readily apparent from the following description and drawings.

In the drawings:

25 Figure 1 is an elevational view of the mechanism within a conventional flush tank, the arrangement being in accordance with the present invention.

Figure 2 is an enlarged detail view in section and elevation showing the principal elements of the improved control valve construction.

Figure 3 is a guide sleeve supporting bracket.

35 Figure 4 is a top plan view of the valve seat fixture.

In the drawings, in Figure 1, the reference character 5 designates the body of the tank, and 6 the removable cover. The water 40 supply pipe is indicated at 7 and this has a valve control at 8, with which the float rod 9 cooperates in any suitable manner. The float is designated by the reference character 10 and is of the usual ball like type. The 45 operating handle is indicated in dotted lines by the reference character 11 and is on the exterior of the tank. It serves to operate a crank arm 12 on the interior having a lifting pin 13. 14 represents the discharge pipe 50 which leads to the hopper (not shown).

Attention is now invited to the control valve mechanism, detailed in Figure 2. To begin with the valve seat fitting is designated generally by the reference character 15. It comprises a screw threaded nipple 55 16 having a flange 17, provided with a valve seat 18.

The flange is disposed substantially flush with the bottom of the tank to insure complete drainage. The reference character 19 designates the retaining nut carried by the nipple. A coupling neck is indicated at 20, and this serves to accommodate the substantially L-shaped or right angular bracket 21. The stem 22 of the bracket is threaded 60 into the neck and held therein by a retaining nut 23. The horizontal arm portion 24 is provided with a two part clamp 25, in which the lower end of the guide sleeve 26 is fitted and held as here shown. There is 65 a top bracket 27, designed to accommodate a rocker arm 28, having an adjustable counter-balance weight 29 and complementary stops 30 and 31 respectively. Connected 70 to the intermediate portion of this rocker arm and depending therefrom into the guide sleeve is a lifting wire 32, having a ring 33 on its lower end which cooperates with an inwardly pressed annular bead 34, on the intermediate portion of the valve tube 35. 75 The valve tube has a similar external bead at 36, and has its lower end fashioned as at 37 to form a connector for the ring nut 38. The ring nut holds the valve annulus 39 in place and in a position to engage the valve 80 seat 18.

In practice, it is obvious that when the handle 11 is rocked in the usual way it actuates the crank arm 12 and through the medium of the pin 13 cooperates with the 85 rocker arm 28, the latter being moved on its pivot, obviously through the medium of the wire 32 and the complementary ring 33 and bead 34, the tube 35 is elevated. This 90 raises the valve 39 off of the seat and allows 95 the water to discharge in an obvious manner. The action of the parts is smooth, dependable and without hitch.

A careful consideration of the description in conjunction with the drawings will enable 100

the reader to obtain a clear understanding of the construction, the assembly, the method of operation, and the features and advantages. Therefore a more lengthy description is believed to be unnecessary.

5. Minor changes in the shape, size and arrangement of details coming within the field of invention claimed may be resorted to, in actual practice, if desired.

I claim:

10. 1. In a structure of the class described, in combination, a fitting embodying a valve seat, a bracket carried by said fitting, a guide sleeve supported from said bracket over said fitting, a second bracket carried by said sleeve, a rocker arm mounted for pivotal movement on said second named bracket, a tube slidable within said sleeve, a valve carried by said tube and cooperable with said seat, and an operating connection 20 between said tube and the intermediate portions of said rocker arm.

2. In a structure of the class described, in combination, a discharge valve construction comprising a fitting including a supporting flange, a depending nipple, a bevelled valve seat, and an attaching neck, an L-shaped bracket detachably connected with said neck, and provided with a clamp disposed centrally above said nipple, a sleeve having its lower end fitted in said clamp, and rising vertically therefrom above said nipple, a rocker arm pivotally mounted from the upper end portion of said sleeve, a tube slidable within said sleeve, said tube being provided with an internal shoulder forming bead, a ring engageable with said bead, a wire connecting said ring with the intermediate portion of said rocker arm, and a 35 detachable valve element on the lower end of said tube cooperable with said valve seat.

3. In a structure of the class described, a fitting for use in association with the valve control mechanism of a flushing tank of the class described comprising a single body including an externally screw threaded nipple, a retaining nut on said nipple, an outstanding annular flange at the top of the nipple, said nipple being provided with a bevelled valve seat, and an upstanding eccentric attaching neck, together with a substantially L-shaped one piece bracket having a screw threaded stem detachably connected with said neck and having its horizontal 50 arm portion provided with a two-part sleeve engaging clamp disposed centrally over said nipple.

4. In a flushing tank valve construction of the class described, a guide sleeve, another 60 valve sleeve telescoped therein, the valve sleeve having a centralized inward annulus, a bracket on the upper end of said guide sleeve extending laterally therefrom, a rocker arm pivotally mounted at one end 65 on the outer end of said bracket, a counter-

balance weight carried by said arm, complementary stops on said rocker arm and bracket, said rocker arm being provided intermediate its ends with a pendant valve sleeve lifting wire depending into the sleeve and provided at its bottom with a ring to cooperate with the inward annulus of the valve sleeve.

5. In a control valve of the class described, an open ended tube provided adjacent its upper end with an inwardly pressed bead constituting a lifting shoulder having its lower end screw threaded and provided above said lower end with an outstanding collar forming bead, a ring nut carried by the screw threaded end portion, a valve 80 annulus between the nut and collar, said valve annulus being provided with a bevelled seating surface.

In testimony whereof I affix my signature.

HENRY CHAS. BRENNAN.
